UNITED STATES PATENT OFFICE.

ALTON F. YEATON AND LEWIS W. BREYFOGLE, OF AKRON, OHIO, ASSIGNEES TO THE STAR DRILLING MACHINE COMPANY, OF AKRON, OHIO, A CORPORATION OF OHIO.

ROPE SOCKET.

Application filed January 2, 1925. Serial No. 79.

To all whom it may concern:

Be it known that we, ALTON F. YEATON and LEWIS W. BREYFOGLE, citizens of the United States, and residents of Akron, 5 county of Summit, State of Ohio, have invented certain new and useful Improvements in Rope Sockets, of which the following is a specification.

This invention relates to rope sockets 10 used in well drilling apparatus.

In the art of well drilling, the drilling tools are carried by a rope or cable passed up from a bull reel over a crown pulley on the top of a derrick or mast. The tools 15 weigh up to three or four thousand pounds and the drilling is effected by raising the tools two to three feet by exerting a pull on the cable and then allowing the tools to drop. Rope sockets are employed for at- 20 taching the tools onto the end of the rope or cable.

During the drilling operations the rope and particularly wire cable transmits severe 25 shocks and strains to the drilling apparatus. Accordingly, there has heretofore been employed in the art, rope sockets in which cushioning means have been employed to take up considerable of the shocks and strains thus to prevent transmission thereof 30 to the machine.

The chief object of the present invention is to provide an improved rope socket wherein 35 shocks and strains will be efficiently absorbed by cushioning means consisting of simple inexpensive and easily replaceable parts which will not be rapidly deteriorated by the percussive action, the action of water or the abrasive action of sand, gravel or the like.

40 The above and other objects will become more apparent as the following description is read in connection with the accompanying drawings in which the preferred form of the invention is illustrated, it being understood 45 that the invention is not limited to the particular form shown and described.

Of the accompanying drawings:

Figure 1 is an elevation of a rope socket embodying the invention; and

50 Figure 2 is a vertical diametral section therethrough.

Referring to the drawings, 10 indicates, generally, the casing of a rope socket which is formed with a vertical bore 11 reduced at 55 its upper end 12 to provide a shoulder 13.

A tube 14 is inserted through the reduced bore 12 in which it is freely slideable and is threaded at its lower end into a block 15 freely slideable and rotatable in bore 11. At its upper end the tube 14 extends out of bore 12 a sufficient distance to permit engagement therewith by a wrench and it is flared outwardly at 14^a on its upper end so as not to cut into or bind onto the rope or cable. The block 15 is formed with a vertical bore 16 communicating with the tube 14 and enlarged at its lower end. The drilling rope or cable 17 passes through tube 14 and bore 16 and the strands thereof are spread out at their lower ends and babbitted in the 70 enlarged portion of bore 16.

Between block 15 and shoulder 13 and encircling tube 14 in bore 11, the improved cushioning means of the invention are placed. These means include annular cushioning elements 18, 18 of non-metallic yielding resilient or elastic material such as rubber which is preferred over other resilient materials because of its waterproof qualities and resistance to abrasion in addition to its 80 elasticity. It has been found that such materials are not subject to crystallization due to the periodic percussions of the drill and thus do not deteriorate from this cause. To position the rubber elements 18 in the bore 11 so 85 that they will have space in which to flow under compression and without binding onto tube 14 a series of washers 19, 19 freely slideable on tube 14 are interposed between the rubber elements 18, the washers being 90 provided with annular lips or shoulders 20, 20 extending perpendicularly from the inner circumference thereof, the shoulder 20 on the lowermost washer being received in a circumferential groove 21 in block 15. The 95 shoulders 20 define a space between the tube 14 and the elements 18 into which the rubber can flow under compression and also the shoulders 20 serve to hold the elements 18 in alignment to prevent their displacement 100 by shocks exerted thereon. The larger diameter of the elements 18 is such that space for the flow of the rubber under compression is provided between the elements 18 and the casing 10.

For holding the above-described parts in the bore 11 of casing 10, a suitable plug 22 is threaded into the lower end thereof, the plug 22 preferably being a standard rope-socket part provided with a tapered thread 110

ed socket 23 for receiving the upper frustoconical threaded end of a drilling tool. The casing 10 is provided with apertures 24, 24 for freely passing water, mud, sand and the like to prevent clogging of the bore 11. To facilitate separation of the casing 10 and plug 23, the casing is formed with a squared portion 25 and the plug with a squared portion 26. In use, the elements 18 provide yielding means for supporting the casing 10 and plug 23 on the block 15 so that as a blow is delivered to the tool, the greater portion of the shock is absorbed by the elements 18 thus relieving the cable and drilling apparatus from severe strains. The tube 14 protects the elements 18 from friction with the cable.

Modifications of the invention may be resorted to without departing from the spirit thereof or the scope of the appended claims.

What is claimed is:

1. In a rope socket, the combination of a casing adapted to be connected to a drilling tool, a block within the casing connected to a cable and means for yieldingly supporting the casing on the block, said means including a cushioning element of rubber.
2. In a rope socket, the combination of a casing adapted to be connected to a drilling tool, a block within the casing connected to a cable and means for yieldingly supporting the casing on the block, said means including a series of cushioning elements of inherently resilient material.
3. In a rope socket, the combination of a casing adapted to be connected to a drilling tool, a block within the casing connected to a cable and means for yieldingly supporting the casing on the block, said means including a series of cushioning elements of rubber.
4. In a rope socket, the combination of a casing adapted to be connected to a drilling tool, a block within the casing connected to a cable and means for yieldingly supporting the casing on the block, said means including a series of cushioning elements of inherently resilient material, and means for holding the elements in alignment.
5. In a rope socket, the combination of a casing adapted to be connected to a drilling tool, a block within the casing connected to a cable and means for yieldingly supporting the casing on the block, said means including a series of cushioning elements of inherently resilient material, and means including other elements interposed with the resilient elements for holding them in alignment.
6. A rope socket comprising, in combination, a casing having means for securing a tool thereon, a bore in the casing for receiving a cable, a slidible block secured on the end of the cable within the bore, a tube encircling the cable above the block and slidible in the bore, and means including an ele-

ment of inherently resilient material encircling the tube for yieldingly supporting the casing on the block.

7. A rope socket comprising, in combination, a casing having means for securing a tool thereon, a bore in the casing for receiving a cable, a slidible block secured on the end of the cable within the bore, a tube encircling the cable above the block and slidible in the bore, and means including an element of waterproof inherently resilient material encircling the tube for yieldingly supporting the casing on the block.

8. A rope socket comprising, in combination, a casing having means for securing a tool thereon, a bore in the casing for receiving a cable, a slidible block secured on the end of the cable within the bore, a tube encircling the cable above the block and slidible in the bore, and means including an element of rubber encircling the tube for yieldingly supporting the casing on the block.

9. A rope socket comprising, in combination, a casing having means for securing a tool thereon, a bore in the casing for receiving a cable, a slidible block secured on the end of the cable within the bore, a tube encircling the cable above the block and slidible in the bore, and means including a series of cushioning elements of inherently resilient material encircling the tube for yieldingly supporting the casing on the block.

10. A rope socket comprising, in combination, a casing having means for securing a tool thereon, a bore in the casing for receiving a cable, a slidible block secured on the end of the cable within the bore, a tube encircling the cable above the block and slidible in the bore, and means for yieldingly supporting the casing on the block including a series of cushioning elements of inherently resilient material and a series of elements interposed with the yielding elements for holding the latter in alignment.

11. A rope socket comprising, in combination, a casing having means for securing a tool thereon, a bore in the casing for receiving a cable, a slidible block secured on the end of the cable within the bore, a tube encircling the cable above the block and slidible in the bore, and means for yieldingly supporting the casing on the block including a series of annular rubber elements and a series of washers formed with lips for positioning the rubber elements in a stack.

12. A rope socket comprising, in combination, a casing having means for securing a tool thereon, a bore in the casing for receiving a cable, a slidible block secured on the end of the cable within the bore, a tube encircling the cable above the block and slidible in the bore, and means for yieldingly supporting the casing on the block including a series of annular rubber elements and a series of washers formed with lips for posi-

tioning the rubber elements in a stack and spacing them from said tube.

13. A rope socket comprising, in combination, a casing having means for securing a tool thereon, a bore in the casing for receiving a cable, a slidable block secured on the end of the cable within the bore, a tube encircling the cable above the block and slidale in the bore, and means for yieldingly 10 supporting the casing on the block includ-

ing an annular cushioning element of inherently resilient material spaced from the tube and from the wall of the casing so that it may flow under pressure.

14. A rope socket comprising, in combination, a casing having means for securing a tool thereon, a bore in the casing for receiving a cable, a slidable block secured on the end of the cable within the bore, a tube 20 encircling the cable above the block and slidale in the bore, and means for yieldingly supporting the casing on the block includ- ing a series of annular rubber elements and a series of washers formed with lips for po- 25 sitioning the rubber elements in a stack spaced from the tube.

15. A rope socket comprising, in combination, a casing have means for securing a tool thereon, a bore in the casing for receiving a cable, a slidable block secured on the end of the cable within the bore, a tube encircling the cable above the block and slidale in the bore, and means for yieldingly supporting the casing on the block includ- ing a series of annular rubber elements and a series of washers formed with lips for positioning the rubber elements in a stack spaced both 35 from the tube and from the casing.

16. A rope socket comprising a casing 40 formed with a portion reduced at its upper

end to form a shoulder, a block slidale in the large part of said bore, a tube mounted on the block, and extending into the reduced portion of the bore, a cable secured to the block and extending through the tube upwardly 45 out of the casing, a stack of annular rubber elements between the block and the shoulder, means for holding the elements in alignment in the stack and means for securing a tool to the casing. 50

17. A rope socket comprising a casing formed with a bore reduced at its upper end to form a shoulder, a block slidale in the large part of said bore, a tube mounted on the block and extending within the reduced 55 part of the bore, a cable secured to the block and extending upwardly through the tube out of the casing, a stack of superposed annular rubber elements and washers encircling the tube between the block and the shoulder, said washers being formed with lips projecting perpendicularly from the inner circumferences thereof to engage the inner peripheries of the rubber elements whereby they will be held in alignment and 60 in spaced relation from the tube, the largest diameter of the rubber elements being such that they will be spaced from the casing, and means for securing a tool to the casing. 65

18. A rope socket comprising, in combination, a casing having means for securing a tool thereon, a bore in the casing for receiving a cable, a slidable block secured on the end of the cable within the bore, and means including an element of rubber encircling 70 the cable for yieldingly supporting the cas- 75 ing on the block.
